UNITED STATES PATENT OFFICE.

NICOLAUS AUGUST OTTO, OF MÜLHEIM-ON-THE-RHINE, GERMANY.

METHOD OF AND APPARATUS FOR THE MANUFACTURE OF COMBUSTIBLE GAS.

SPECIFICATION forming part of Letters Patent No. 252,503, dated January 17, 1882.

Application filed May 24, 1881. (No model.) Patented in England May 4, 1881, in France May 10, 1881, in Belgium May 17, 1881, in Italy May 31, 1881, and in Spain August 5, 1881.

To all whom it may concern:

Be it known that I, NICOLAUS AUGUST OTTO, a citizen of Prussia, residing at Mülheim-on-the-Rhine, in the German Empire, have invented an Improved Method of and Apparatus for the Manufacture of Combustible Gas, of which the following is a specification.

My invention relates to the production of combustible gases rich in combustible matter in gas-producers operating on the continuous system.

In the manufacture of combustible gas in gas-producers two processes take place: First, the combustion of the coal or carbonaceous matter with the incoming air at or near the grate results in the production of carbonic-acid gas, together with nitrogen, under development of heat; and, secondly, the carbonic-acid gas, in passing through the upper layer of incandescent fuel, takes up a further quantity of carbon and becomes converted into carbuncle oxide. On the completion of these processes a small excess of heat remains in the producer, by means of which steam can be decomposed by 25 the aid of the fuel into pure carbonic oxide and hydrogen.

According to my present invention I produce a gas that is richer in combustible matter than the aforesaid ordinary producer-gas by the following process: Instead of allowing the whole of the carbonic-acid gas produced in the first instance to be converted into carbonic oxide, I cause a portion thereof, together with the accompanying nitrogen, to pass away out of the producer. Although by this means a portion of the heat produced by the generation of and retained by the said gases is withdrawn from the producer, yet a very considerable portion of such heat still remains, by means of which I am enabled to decompose either undiluted carbonic-acid gas or steam or carbureted hydrogen to take the place of the carbonic-acid gas diluted with nitrogen that has been withdrawn. In the following I shall only refer to the use of steam. The more gaseous products of combustion are removed from the producer the less of such products will remain in the same for furnishing producer-gas, and in the same proportion, therefore, a larger quantity of steam 45 can be decomposed into pure carbonic oxide

and hydrogen, and consequently a richer combustible gas be produced. On the other hand the heat contained in the gaseous products of combustion that are withdrawn can be utilized either for the production and superheating of 55 the steam to be employed, as above described, or for any other purpose.

The above-described method of operating may be conveniently carried out by means of the construction of gas-producer shown on the accompanying drawings, in which Figure 1 shows a vertical section, and Fig. 2 a sectional plan, of the producer.

Those parts hereof which are similar to those of producers of known construction need not 65 be further referred to. The parts that are new are the lateral chamber *a* and the passages *b b b*, by which this chamber communicates with the interior of the producer, and by which a portion of the carbonic acid and nitrogen 70 is withdrawn from the producer, the said passages *b* being for this purpose situated near to the fire-grate *c*, where no carbonic-oxide gas has as yet been formed. The gases that are thus withdrawn escape through the pipe 75 *d* after having given up a portion of their heat in the chamber *a* to the pipes *e* and *f*, the proportion of gases withdrawn being regulated by the cock *g*. Steam being thus formed or superheated in the pipes *e* and *f*, that from *e* is 80 employed as a steam-jet below the grate for propelling the necessary air into the producer through the opening *i*. Assuming the producer to be charged with fuel in the usual manner through a hopper, *l*, with shut-off valve *m*, 85 and ignited, the air introduced at *i* will by the combustion above the grate *c* be decomposed, forming carbonic acid and nitrogen, of which a portion will be led away through the passages *b*, while the remainder will be converted 90 into producer-gas on rising through the heated fuel above. At the same time the steam produced in the pipe *f* is led by a pipe, *h*, at one or more points, into the producer, where it is converted by the incandescent fuel into carbuncle oxide and hydrogen, which combine with the other producer-gases and pass away with them through the pipe *k* to wherever required 95 for use.

For producing a regulated supply of steam 100

to the pipes *f*, water may be made to flow in a regulated quantity from a vessel, *n*, into the funnel-mouth of a pipe, *o*, through which it flows into the lowest coil of the pipe *f*, to be there converted into steam.

The steam for the steam-jet *e* may be supplied from a separate generator through a pipe, *p*. I am aware that a patent is being applied for by E. Langen for withdrawing combustible 15 gas from the producer to carbonic-oxide gas at some height above the fire-grate in gas-producers, in order by its combustion outside the producer to generate heat for decomposing steam, and I do not claim such a method of operating.

I am also aware that in the manufacture of gas for illuminating and heating purposes the gas-producing material has been caused to traverse slowly through a generator, where it is subjected to a continuous or increasing high temperature and distilled to different degrees, after which the different grades of gas are independently drawn off at different points in the generator, steam being admitted to the furnace below the grate for supplying hydrogen, and the gas purified for removing the carbonic acid resulting from the union of the oxygen of the steam with the carbon of the coke in the furnace. Such, however, does not constitute my invention, and is hereby disclaimed.

Having thus described the nature of my in-

vention and in what manner the same is to be performed, I claim—

1. The within-described method of producing combustible gases in gas-producers, the same consisting in developing carbonic-acid 35 gas and nitrogen by the combustion of carbonaceous fuel, then drawing off a part only of the carbonic acid and nitrogen at a point directly above the grate of the producer and below the main body of fuel, then converting 40 the remaining portion of carbonic-acid gas and nitrogen into producer-gas, and finally introducing steam directly into the body of the incandescent fuel at a point above the grate of the producer, for converting the steam into carbonic oxide and hydrogen, which combine with the producer-gas, all substantially in the manner and for the purposes described.

2. The gas-producer provided with passages 45 *b*, *b*, in combination with the chamber *a*; flue-pipe *d*, cock *g*, and steam-pipes *f*, *e*, and *h*, substantially as and for the purpose described.

In testimony whereof I have signed my name to this specification, in the presence of two subscribing witnesses, this 3d day of May, A. D. 1881.
